UNITED STATES PATENT OFFICE.

FRIEDRICH MÜNZINGER, OF BERLIN, GERMANY, ASSIGNOR TO THE FIRM ALLGEMEINE ELEKTRICITÄTS-GESELLSCHAFT, OF BERLIN, GERMANY.

FUEL ECONOMIZER.

Application filed September 3, 1921. Serial No. 498,526.

To all whom it may concern:

Be it known that I, FRIEDRICH MÜNZINGER, a citizen of Germany, residing at Berlin, Germany, have invented certain

5 new and useful Improvements in Fuel Economizers (for which I have filed applications in Germany, October 7, 1915, No. 302,351; Great Britain, May 15, 1920; No. 143,271; Czechoslovakia, June 8, 1920; 10 Italy, July 6, 1920; France, July 10, 1920, No. 520,213; Austria, July 12, 1920; Hungary, December 28, 1920; Poland, January 21, 1921; Netherlands, January 24, 1921), of which the following is a specification.

15 My invention refers to fuel economizers or feed water heaters of the class which comprise upper and lower headers and a series of vertical circulating tubes connecting each lower header with the corresponding upper header. It is an object of the present invention to improve the mechanical construction and arrangement of this type of fuel economizer.

In economizers of the class above specified 20 as hitherto constructed the vertical circulating tubes are of uniform length and the headers are juxtaposed either in contact with or in comparatively close proximity of one another whereby a throttling effect is exerted upon the heating gases. This might be avoided by spacing the tubular members together with the headers farther apart, but then the velocity of the gases would be unduly diminished whereby the quantity of 25 heat absorbed in the unit of time would be badly influenced.

In order to obviate these drawbacks and to provide for a sufficiently wide passage between the headers without spacing the tubes 30 further apart, I employ tubes of different length arranged in such manner that their upper ends which are connected with the upper headers are disposed all on one level, the upper headers providing a gas tight closure, while the lower ends of the tubes 35 and the lower headers connected thereto are arranged at different levels, whereby the gases are allowed a free passage between the lower headers and along the circulating tubes in close contact therewith and at equal 40 velocity.

In the drawings affixed to this specification and forming part thereof two modifications of an economizer embodying my in-

vention are illustrated diagrammatically by way of examples. In the drawings—

Figure 1 is a vertical longitudinal section, and

Figure 2 is a vertical cross section of an economizer in which the gases enter from below and after having passed through between the circulating tubes, leave the economizer again through a bottom flue. 60

Figures 3 and 4 are similar views showing a modification in which the gases enter and leave the device through openings provided in the top end thereof.

Referring first to Figs. 1 and 2 of the drawings, *a* is the masonry wall of the economizer chamber and *b* is a central partition 70 the upper end of which is spaced apart from the top wall and which divides the chamber in two compartments *c* and *d* which are in communication by way of the passage *e* above the partition. The gases enter at *f* 75 and leave at *g* as shown by the arrows.

k, *k'* are the vertical circulating tubes, *l*, *l* are the upper headers disposed in the top wall in close juxtaposition, thus providing a 80 gas-tight closure. *p* is a main collecting the water from the upper headers.

The vertical tubes differ in length, rows of longer tubes *k* alternating with rows of shorter tubes *k'*. Each row of longer tubes *k* is connected with a lower header *m*, while 85 each row of shorter tubes *k'* is connected with a lower header *n*. Owing to the different length of the tubes *k* and *k'*, respectively, the lower headers *m* and *n* are located on different levels, their horizontal 90 collecting tubes *t*, *t'* being connected by bends *o*.

As can easily be seen from the drawing, although the vertical circulating tubes are not spaced farther apart than in the devices 95 hitherto in use, the entrance afforded to the gases into the space filled with tubes and their escape therefrom are greatly facilitated by the lower headers being arranged in staggered relation. 100

In the modification illustrated in Figs. 3 and 4 the partition *b'* extends from the top wall down to the base portion of the economizer. The entrance and exhaust ports *f'*, *g'* are arranged in the top part of the side walls and the transversal passage *e'* connecting the two chambers *c'*, *d'* below the lower headers. *h* is an ash-pit closing the

2
 chambers below and having an opening *i* arranged therein. In all other respects the arrangement of parts is the same as explained in connection with Figs. 1 and 2.

5 The gases enter at *f'* and leave at *g'*, the staggered arrangement of the lower headers providing a free and easy passage.

I wish it to be understood that I do not desire to be limited to the exact details of 10 construction shown and described for obvious modifications will occur to a person skilled in the art.

I claim:—

1. Fuel economizer comprising in combination, juxtaposed rows of substantially vertical circulating tubes, the tubes in alternating rows differing in length, the upper ends of all the tubes being disposed at the same level, juxtaposed upper headers arranged in 15 close contact with one another connecting the upper ends of said rows of tubes, lower headers connecting the lower ends and being
- 20

disposed at two different levels and means for causing heating gases to travel lengthwise of said tubes and to enter and leave between the lower headers. 25

2. Fuel economizer comprising in combination, a chamber, a central partition subdividing said chamber so as to form a U-shaped passage, juxtaposed rows of substantially vertical circulating tubes in either branch of said passage, the tubes in alternating rows differing in length, a series of juxtaposed headers arranged all on one level in close contact with one another and connecting one end of all the tubes, two series 30 of headers arranged on two different levels connecting the other ends of said tubes, and means for causing hot gases to travel lengthwise of said tubes through said U-shaped 35 passage, so as to enter and leave between said staggered headers. 40

In testimony whereof I affix my signature.

FRIEDRICH MÜNZINGER.
